BRACE BAR SECURING MEANS FOR PREFABRICATED TUBULAR STRUCTURES

Marvin M. May, Los Angeles, Calif., assignor to Tubular Structures Corp. of America, Los Angeles, Calif., a corporation of California

Filed Apr. 25, 1958, Ser. No. 730,987

4 Claims. (Cl. 287—53.5)

This invention relates to tubular structures and more particularly to prefabricated tubular structures and still more particularly to prefabricated tubular structures of the knock-down type and has for its object the provision of an improved means for detachably securing together the load-supporting standards of such prefabricated tubular structures.

Another object of the invention is to provide an improved means for detachably securing together the load-supporting elements of a knock-down tubular structure, such as scaffolds and the like.

Still another object is to provide a means integrally mounted on the tubular structure of the knock-down type for detachably securing the load-supporting standards together.

A further object is to provide an improved scaffold of the knock-down prefabricated type.

Other objects will be apparent as the invention is more fully hereinafter disclosed.

In accordance with these objects, I have devised an improved means for detachably securing together the component parts of a prefabricated tubular structure, such as the load-supporting standards of a scaffold, which means is adapted to be permanently mounted upon the load-supporting standards of the tubular structure. One specific embodiment of the improved means of the present invention is illustrated in the drawings by way of example but not as a limitation.

In the drawings:

Fig. 1 is a perspective view of one type of a prefabricated knock-down tubular scaffold structure improved in accordance with the present invention;

Fig. 2 is an enlarged sectional view of the improved means of the present invention taken along plane 2—2 of Fig. 1 showing the means in one operating position;

Fig. 3 is a sectional view taken along plane 3—3 of Fig. 2; and

Fig. 4 is a broken away sectional view along plane 2—2 of Fig. 1 showing the improved means of the present invention in a second operating position.

The specific embodiment shown in the drawings discloses the improved means of the present invention as it has been adapted for utility in a prefabricated tubular structure of the type known in the art as a scaffold.

In this type of tubular structure, as indicated in Fig. 1, the scaffold is comprised of a plurality of pairs of vertically sustained load carrying members consisting of tubular standards S—S', secured together in parallel spaced relation by tubular cross-bars C—C' and center vertical tubular upright D with or without associated tubular cross-bar members E—E', the plurality of pairs of load carrying members S—S' being detachably secured together in parallel spaced relation by brace-bars B—B' detachably secured at each end to the standards S—S (S—S') adjacent the top and bottom of the standards S—S (S—S') by a securing means M, improved in accordance with the present invention.

2

The means M, in conformity with the present invention, is comprised essentially of a pair of parallel spaced pins 10—10' having one end secured to the standard S, with each provided adjacent the opposite end thereof with a transverse slide pin opening 15—15' of substantially the same size, shape and configuration. The means securing the ends of the pins 10—10' in parallel spaced relation to the standard S adjacent one end of the standard S may vary widely without departure from the invention.

10 The pins 10—10' are mounted on the standard S in such manner as to dispose the slide openings 15—15' in axial alignment and lying in a plane parallel to the longitudinal axis of the standard S. A slide pin means 16 is slidably mounted in the aligned slide pin openings 15—15', the length of said slide pin means 16 being substantially greater than the distance between the two pins 10—10'. An extension 17 is provided on the inside face of the slide pin means 16, the width of said extension being such that it snugly engages the side 15 of the perforated end 22 of a brace bar B mounted on the lower pin 10' substantially as shown in Fig. 2 of the drawings, to hold the bar B against undue lateral movement on pin 10'.

In the specific embodiment shown in the drawings, 25 the slide pin 16 comprises a tongue slide pin 16 as a preferred type. It is believed obvious, however, that other types of slide pins 16 may be employed without departure from the invention. The type of slide pin 16 shown is readily adapted to be formed from strip or 30 sheet metal, such as an iron or steel alloy and the thickness of the same may be readily adapted to any diameter of pin 10—10'.

With reference to pins 10—10', the diameter of the 35 pins may be varied widely without essential departure from the invention to adapt same for application to various sizes of tubular standards S—S'. In general, for most prefabricated scaffold structures of the type illustrated in the drawings the tubular standards S—S' are comprised of steel pipe of approximately 1½ inches outside diameter and 1.445 inches inside diameter. With this size standard the pins 10—10' are each about ½ inch in diameter. With this size pin and for this size scaffold structure the slide tongue-pin 16 is comprised of a ¼ inch strip of steel approximately ⅜ inch in width. 40 The preferred spacing between the pins 10—10' on the standard is approximately 2 inches. With this spacing between the pins 10—10' the slide tongue-pin 16 is provided with a length approximating 3¾ inches. The slide pin openings 15—15' are rectangular in cross-section loosely conforming to the rectangular cross-section of the slide tongue-pin 16.

The particular manner by which the pins 10—10' are secured in desired spaced relation to the standard S may be widely varied without essential departure from the 55 invention as one skilled in the art will recognize.

In the arrangement shown, the pins 10—10' are preferably first secured to a back-bar 11 in desired spaced relation with the slide openings 15—15' therein in axial alignment and the back-bar 11 thereafter is secured to the standard S in any desired manner, as by welding as 60 indicated at 12—12'. This arrangement has been found to be the most economically practical method for mounting the pins 10—10' upon the standard S and is of particular utility where the means M is to be marketed as a unitary assembly for the installation by the purchaser upon prefabricated structures then in use in substitution for those heretofore employed herewith. Alternatively, the pin ends may be secured directly to the standard S in desired spaced relation without the use of back-bar 65 11 without departure from the invention, as by welding the ends thereto or in any other manner.

In the particular U-type arrangement of the means M

shown in the drawing a length of round or square bar steel stock is formed by either hot or cold forming methods into a substantially U-shaped member with the extending arms thereof forming the pins 10—10' extending in the desired parallel spaced relationship therefrom. The extending arms are cut off to provide the desired pin length, the slide openings 15—15' are made therein, tongue slide pin 16 is mounted in the slide openings 15—15' and the wedge extension 17 is then secured to the side edge of the tongue slide pin 16 in any convenient manner, as by welding. Where round stock is employed in the forming of this unitary structure the outer face of the bight section 11 of the structure is flattened during the forming operation, preferably slightly concaved, to adapt the section 11 to seat itself tightly onto the rounded surface of the standard S. Similarly, where bar stock is employed, the outer surface of the bight section 11 is concaved during the forming operation to seat on the rounded surface of the standard S.

It is believed obvious that various alternative means for securing the bight section 11 to the standard S in substitution for the weld joints 12—12' may be employed without substantial departure from the invention and that within the scope of the invention the means employed may be either a means for fixedly securing or a means for detachably securing the bight section 11 to the standard S.

Referring to Figs. 2 and 4 it will be noted that two operating positions of the tongue slide 16 are disclosed therein. The distance between the edge of slide tongue 16 and the face of the bight section 11 is preferably selected with respect to the thickness of the perforated flattened end 22 of the brace-bar B to be approximately equal to twice this thickness and the width of the extension 17 is preferably selected to be approximately equal to the thickness of the flattened end 22. With this arrangement it will be noted that, as shown in Fig. 2, with only one end 22 mounted on the pin 10' the slide tongue 16 may be lowered in its slide opening 15' to a position wherein the outer face of the extension 17 secures the end 22 on the pin 10'. When the slide tongue 16 is in this position it is frequently desirable to secure the slide tongue 16 against vertical movement. To provide for this a pin opening 20 is provided in the slide tongue 16 in a position adjacent to the under face of the pin 10' into which a pin may be inserted to prevent vertical movement of the slide tongue 16 in the slide opening 15'.

Where two said flattened ends 22—22' are mounted on the pin 10', as indicated in Fig. 4 of the drawings, the slide tongue 16 can only be lowered in the slide opening 15' to the point where the extension 17 rests upon the top of one of the ends 22'. In this position of the slide tongue 16 the side edge of the slide tongue 16 secures the ends 22—22' upon the pin 10'. To secure the slide tongue 16 from vertical displacement a second pin opening 21 is provided in the tongue end in a position to adapt a pin inserted therein to engage the under face of the pin 10' to restrain vertical movement of the slide tongue 16.

To facilitate the raising and lowering of the slide tongue 16 the extension 17 is provided with at least one, and preferably two, side extensions 18—19 providing for manual engagement. These extensions 18—19 may be of any desired size, shape and configuration. In the specific embodiment the extensions 18—19 are shown as bent over sections of the upper and lower edges of the extension 17. Various other substantially equivalent raising and lowering means may be provided, however, without essential departure from the invention.

It is believed apparent that in operation the plurality

of means M of the present invention located as indicated in Fig. 1 and adjacent each end of the standards S—S' are adapted to secure the flattened perforated ends 22 of the plurality of cross-bars B upon the standards 5 S—S' in the scaffold structure shown with substantial ease and facility by lifting the slide tongue 16 out of engagement with the slide opening 15' in pin 10' to a horizontal level permitting the flattened ends 22 to be mounted on the pin 10'. On lowering the slide tongue 16 into engagement with its slide opening 15' the ends 22—22' then are secured in position on the pin 10' against lateral displacement thereon. The frictional engagement of either the extension 17 or the side edge of the tongue 16 with the ends 22—22' effectively restrain the ends 22—22' against rotative movement on the pin 10' thereby stabilizing the scaffold structure against side sway in both directions. When the slide tongues 16 are restrained against vertical movement by pins disposed on openings 20 or 21 the entire scaffold structure is secured against side sway.

It is believed apparent that many modifications, changes and substitutions may be made in the invention as illustrated in the specific embodiment of the drawings as hereinabove described without essential departure from the nature and scope of the present invention and all such are contemplated as may fall within the scope of the following claims.

What is claimed is:

1. Means for securing the perforated end of a brace-bar to a vertically upright standard, said means comprising a substantially U-shaped member, the bight section of said member being secured onto said standard with the U-arms thereof extending outwardly therefrom in alignment with the longitudinal axis of said standard, the lower of said arms having a size, shape and configuration to permit the perforated brace-bar end to be seated thereon, slide pin openings adjacent the ends of said U-arms, the axes of said slide pin openings being coincident and lying in the same plane parallel to the longitudinal axis of the standard, a slide pin disposed in said slide pin openings the length thereof being substantially greater than the spacing therebetween and an extension on the inner face of said slide pin having a width adapted to slidably engage a brace-bar end engaged on said lower U-arm to engage and hold the brace bar substantially against said bight portion.

2. The means of claim 1, the length of said lower U-arm being substantially equal to twice the thickness of said brace-bar end between the inner edge of said slide pin and the inner face of said bight section and the width of said extension being substantially equal to the thickness of one said brace-bar end and the length of said slide pin below said extension engaging in and extending below a slide pin opening in the lower said U-arm when the said wedge extension rests upon one said brace-bar end.

3. The means of claim 1, pin openings in the extending end of said slide pin below the said lower U-arm, said pin openings being located in positions, whereby a pin member inserted therein secures the slide pin against longitudinal movement in the slide pin opening.

4. The means of claim 1, said bight section being provided with a concaved outer face for the face to engage the cylindrical surface of a tubular standard.
